(57) **CLAIM**

The ornamental design for a signaling device, as shown and described.

DESCRIPTION

FIG. 1 is a front perspective view of a signaling device.

FIG. 2 is a rear perspective view of the signaling device shown in FIG. 1.

FIG. 3 is a front elevational view of the signaling device shown in FIG. 1.

FIG. 4 is a rear elevational view of the signaling device shown in FIG. 1.

FIG. 5 is a top plan view of the signaling device shown in FIG. 1.

FIG. 6 is a bottom plan view of the signaling device shown in FIG. 1.

FIG. 7 is a right side elevational view of the signaling device shown in FIG. 1; and,

FIG. 8 is a left side elevational view of the signaling device shown in FIG. 1.

1 Claim, 8 Drawing Sheets
